UNITED STATES PATENT OFFICE.

BURTON R. STARE, OF CHICAGO, ILLINOIS.

JOURNAL-LUBRICATOR.

SPECIFICATION forming part of Letters Patent No. 740,482, dated October 6, 1903.

Application filed May 22, 1903. Serial No. 158,283. (No model.)

To all whom it may concern:

Be it known that I, BURTON R. STARE, a citizen of the United States, residing at Chicago, in the county of Cook and State of Illinois, 5 have invented a new and useful Improvement in Journal-Lubricators, of which the following is a specification.

My invention relates particularly to journal-lubricators for cars and the like; and my 10 primary object is to provide a simple, durable, and inexpensive device of this character, particular attention being paid to securing the lubricating-roller against injury, insuring its constant immersion in oil, and providing for "jacking up" the journal-box with relation to the journal when needful for 15 repairs or renewal of parts.

The invention is illustrated in its preferred embodiment in the accompanying drawings, 20 in which—

Figure 1 represents a longitudinal sectional view of the journal-box of a car with the journal in place and equipped with my improvements; Fig. 2, a horizontal section taken as 25 indicated at line 2 of Fig. 1, the journal being removed; Fig. 3, a section taken as indicated at line 3 of Fig. 1, and Fig. 4 an enlarged section taken as indicated at line 4 of Fig. 3 and showing a detail of the universal 30 connection employed between the roller-frame and its support.

A represents a journal-box of the ordinary construction equipped with a brass bearing A', a wedge A², and a dust-guard A³; B, a 35 journal of the usual construction provided at its free extremity with an annular flange B'; C C', oiling devices serving to supply oil to the journal; D, a lug projecting upwardly from the central outer portion of the bottom 40 of the journal-box and having its upper end located directly beneath the flange B'; E, lugs with which the inner surface of the bottom of the journal-box is equipped at a central transverse plane and which afford between them a transverse channel receiving 45 an oil-guard E', and E² an oil-guard projecting inwardly from the upper edge of the lower portion of the inner wall of the dust-guard cavity.

Each of the devices C C' comprises a short inclined roller-frame a, with suitably-spaced

side members a' and connecting end members a² a³, a roller a⁴, antifrictionally journaled on a shaft a⁵, having angular ends fitting within sockets, with which the side members of the frame are provided centrally at their upper edges, a horizontally-disposed frame-supporting hook or stud a⁶, having screw connection with one side of the journal-box a short distance above the bottom of 60 the box and having universal connection with the end a² of the roller-frame, a spring a⁷, connected with the free end of the roller-frame, and a spring-supporting stud or hook a⁸, having screw connection with the opposite 65 wall of the journal-box in the same transverse plane as the hook a⁶. The hook portion of the member a⁸ is of a width enabling it to fit loosely between the side members of the roller-frame and embrace the end 70 member a². Said hook portion is provided centrally with a concavity b, extending longitudinally of the hook and following the contour thereof. The end member a² is of substantially circular cross-section, with a 75 flange b' at its upper portion extending longitudinally of the end member. The end member is provided on its sides and lower portion centrally with a circumferential convexity b², which fits in the concavity b. Thus 80 the frame a is capable of swinging in a transverse vertical plane, the flange b' working in the space b² between the extremity of the hook and the shank of the hook, and also the frame is capable of swinging in a longitudinal plane about the bearing b b² within 85 limits. Thus the frame has practically a universal movement within limits and yet is securely held upon its support. The spring 90 serves to hold the lubricating-roller firmly against the journal.

From Fig. 2 it will be understood that the oiling devices C C' are arranged in different transverse planes, and from Fig. 3 it will be understood that the lubricating-rollers of the 95 two oiling devices are located on opposite sides of the journal and journaled in their frame some distance below the universal supports of the frames. Each frame being short and virtually depending from its support 100 enables the necessary movement of the lubricating-roller to occur when it is necessary to

- "jack up" the body of the car or lift it from the trucks for purposes of repair or for other purposes. The springs hold the lubricating-rollers firmly in contact with the journal, 5 and as the bearing A' wears the roller-frames are drawn upwardly. The extreme wear on the bearing A', which is permissible, is indicated by the dotted lines in Fig. 3, and the upper dotted positions of the rollers α^4 indicate their position after such wear has occurred. The lower dotted positions of the rollers indicate the positions to which they are capable of swinging when the journal-box is raised with relation to the journal, 15 and the lower dotted position of the journal indicates its lowest possible position with relation to the journal-box, the lug D in this position serving to support the journal and prevent crushing of the rollers.
- 20 The lug D has its top separated from the flange B' of the journal by a space c, which should be short enough to cause the flange to engage the lug before a crushing pressure can be brought upon the rollers.
- 25 The oil-guard E' comprises, preferably, a sheet-metal member folded upon itself, the folded margin being inserted between the lugs E and the upper edges being bent away from each other to afford the flanges. The 30 oil-guard E² is preferably formed integrally with the inner wall of the dust-guard cavity and has a curvature corresponding with the curvature of the journal-opening. To permit the journal-box to tilt somewhat with 35 relation to the journal in a longitudinal plane, the inner wall d of the dust-guard cavity is cut away below the outer wall d' of said cavity at the lower portion of the dust-guard cavity.
- 40 It will be understood that the universal connections of the roller-frames permit the rollers to adjust themselves with relation to the journal, rendering the frames self-righting, so that the rollers maintain line-contact with 45 the journal. The feature of the upper edge of the lower portion of the inner wall of the dust-guard cavity terminating beneath the upper edge of the lower portion of the outer cavity provides for a return to the journal- 50 box of any oil which may accumulate in the cavity. The oil-guard E² effectually prevents the loss of oil by splashing, as when the car is rounding a curve.
- In the construction shown the roller-frame 55 supports have screw connection with the side walls of the journal-box, as do the spring-supports. This enables the oiling devices to be applied to journal-boxes already in use. It will be understood, however, that the supports for the roller-frames may be arranged in any suitable manner without departure from my invention. It further will be understood that other changes in details of construction within the spirit of my invention may be 60 made. Hence no undue limitation should be understood from the foregoing detailed de-

scription, which has been given for clearness of understanding only.

What I regard as new, and desire to secure by Letters Patent, is—

1. The combination with the journal-box and journal of a car, of a stud within said journal-box and having threaded connection with a wall thereof, a short roller-frame movably supported directly thereon having both 75 a self-righting and a wear-compensating movement with relation to said stud, a lubricating-roller journaled on said frame, and means for yieldingly holding the frame to cause the roller to bear against the journal, 80 for the purpose set forth.
2. The combination with the journal-box and journal of a car, of a stud within said journal-box and having threaded connection with a wall thereof, a short transversely-extending roller-frame having one end supported directly thereby, said frame being capable of a self-righting and a wear-compensating movement, a suitably-sustained spring 85 connected with the free end portion of said 90 roller-frame, and a lubricating-roller journaled on said frame, for the purpose set forth.
3. The combination with the journal-box and journal of a car, of a stud projecting inwardly from one side of the journal-box, a 95 short swinging roller-frame having one end supported on said stud, a spring connected with the free end of the roller-frame, and with the opposite side of the journal-box, and a roller journaled on said frame beneath and 100 adjacent to said stud and bearing against said journal and capable of moving into the corner of the journal-box directly beneath said stud, for the purpose set forth.
4. The combination with the journal-box 105 and journal of a car, of supports near the lower portions of opposite sides thereof, a short self-righting downwardly-swinging frame having one end borne by one support, a spring connecting said frame with the opposite support, and a lubricating-roller journaled on said frame, for the purpose set forth.
5. The combination with the journal-box and journal of a car, of a stationary support, a short roller-frame having suitably-spaced 115 sides and one end universally joined to said stationary support, a suitably-sustained spring holding the free end of said frame normally raised, and a roller located between the side members of said frame and bearing 120 against the journal, for the purpose set forth.
6. The combination with the journal-box and journal of a car, of a pair of self-righting short roller-frames located in different transverse planes on opposite sides of the longitudinal central plane of the journal, a support adjacent to the outer end of each frame and having universal connection therewith, a roller journaled in each frame some distance beneath the universal connection thereof, and 125 springs holding said frames normally elevated, for the purpose set forth.

7. The combination with the journal-box and journal of a car, of a supporting-hook, a roller-frame having a transverse pin at one end, a concavity and convexity bearing between said hook and pin allowing self-righting of the frame, a roller journaled in said frame, and a spring connecting said frame with a stationary part, for the purpose set forth.

8. The combination with the journal-box and journal of a car, of a horizontal hook screwed into one side wall of the journal-box adjacent to the lower corner thereof, a short roller-frame pivoted thereon, a roller journaled in said frame below and adjacent to said hook, a spring-support screwed into the opposite side of the journal-box, and a spring connecting the free end portion of said roller-frame with said spring-support, for the purpose set forth.

9. The combination with a car journal-box and its journal projecting thereinto, of a lug on the bottom of the journal-box directly be-

neath the extremity of the journal, substantially as and for the purpose set forth. 25

10. The combination with a car journal-box and its journal projecting thereinto, of a set of lugs on the bottom of the central portion of the journal-box, affording a transverse channel, and a member of sheet material confined by said channel and having oppositely-projecting flanges above said lugs, for the purpose set forth.

11. The combination with a car-journal, of a journal-box having a dust-guard cavity at 35 its inner end, the upper edge of the lower portion of the inner wall being beneath the upper edge of the lower portion of the outer wall, and having a curved inwardly-projecting flange constituting an oil-retainer, for the 40 purpose set forth.

BURTON R. STARE.

In presence of—

WALTER N. WINBERG,
M. I. MACKENZIE.
